(57) CLAIM

The ornamental design for a wall mounted desk with storage, as shown and described.

DESCRIPTION

FIG. 1 is a top perspective view of a wall mounted desk with storage showing the new design;

FIG. 2 is a bottom perspective view thereof;

FIG. 3 is a rear perspective view thereof;

FIG. 4 is a front elevational view thereof;

FIG. 5 is a rear elevational view thereof;

FIG. 6 is a side elevational view thereof, the other side being a mirror image;

FIG. 7 is a top plan view thereof;

FIG. 8 is a bottom plan view thereof; and,

FIG. 9 is an exploded perspective view thereof.

The broken lines shown in the figures represent portions of the wall mounted desk with storage that form no part of the claimed design.
